UNITED STATES PATENT OFFICE.

EDWARD WILLIAM MACKENZIE HUGHES, OF CHICAGO, ILLINOIS, ASSIGNOR
TO THE FOX SOLID PRESSED STEEL COMPANY, OF SAME PLACE.

TRUCK-FRAME.

SPECIFICATION forming part of Letters Patent No. 408,024, dated July 30, 1889.

Application filed January 3, 1889. Serial No. 295,324. (No model.)

To all whom it may concern:

Be it known that I, EDWARD WILLIAM MACKENZIE HUGHES, of Chicago, Cook county, Illinois, have invented a new and useful Improvement in Truck-Frames, of which the following is a full, true, and exact description, reference being had to the accompanying drawings.

In the manufacture of truck-frames for moving vehicles, especially truck-frames for railroad-cars, it has been very difficult to insure the exact rectangular arrangement of the side and end frames, and to continue said rectangular structure when the frame has been made, these frames generally having been made of castings or of hand-wrought material, and in many instances in part of wood. By my improvement I propose to make these frames entirely of pressed steel, in which the parts are made of steel pressed between dies of such shape as to necessarily insure the rectangular formation when the frames have been put together. This I accomplish by flanging the side and end frames in such manner that these flanges fitting together necessarily insure the rectangular shape previously referred to. By making these frames of pressed steel, as described, I likewise insure greater uniformity of material, greater lightness, and an increased durability.

My invention will be readily understood from the accompanying drawings, in which—

Figure 1 represents a view of the bottom of my truck-frame; Fig. 2, a cross-section of the mode of connection of the bolster-beam box and side frame; Fig. 3, an inside view of the side frame; Fig. 4, an outside view of the same; Fig. 5, a section through the end frame, showing its method of attachment to the side frame; and Fig. 6, a section at right angles through Fig. 5.

A and B are the side frames, C and D the end frames, and F the bolster-beam box. These frames A, B, C, and D are substantially box-shaped, having bottoms and sides and rectangular corners adapted to fit into each other, as hereinafter to be described. They are preferably made upon the apparatus for which application has been made by Samson Fox on the 18th day of January, 1888, Serial No. 261,166. The rectangular boxes C and D are arranged to fit over the ends of the side

frames A and B, and the flanges of the side frames come in contact, making an accurate fit with the insides of the boxes C and D, as 55 clearly shown in Figs. 5 and 6. By simply, therefore, bringing these flanges, which necessarily accurately correspond, being pressed in similar dies, into fitting contact there is made an absolutely rectangular frame. The 60 bolster-beam box having been put in position through its proper openings, as shown in Fig. 4, the side frames are riveted or suitably attached at the corners, (they may be welded, if preferred,) and the bolster-beam box is like- 65 wise riveted, making a rigid and accurately rectangular frame.

I do not herein claim the invention claimed in my companion application, Serial No. 295,322. 70

What I claim as my invention, and desire to secure by Letters Patent, is—

1. The combination of the pressed-steel flanged side frames A and B and the pressed-steel flanged end frames C and D, the flanges 75 of said frames accurately fitting against each other, so as to produce an accurately rectangular frame, substantially as described.

2. The combination of the pressed-steel side frames A and B, having flanges at right angles 80 to their main plane, and the pressed-steel flanged end frames C and D, having their flanges at right angles, fitting accurately the flanges of the side frames A and B, and the whole firmly attached by riveting or welding, 85 so as to insure a rectangular frame, substantially as described.

3. The combination of the pressed-steel side frames A and B, having flanges at right angles to their main plane, and the pressed-steel 90 flanged end frames C and D, having their flanges at right angles, fitting accurately the flanges of the side frames A and B, and the bolster-beam box F, fitting the flanged side frames A and B, the whole firmly attached by 95 riveting or welding, so as to insure a rectangular frame, substantially as described.

In testimony whereof I have signed my name to this specification in the presence of two subscribing witnesses.

EDWARD WILLIAM MACKENZIE HUGHES.
